Hawson & Hawson

UNITED STATES PATENT OFFICE.

EUSTACHIUS JOSEPH KING, OF PHILADELPHIA, PENNSYLVANIA.

RAILROAD SWITCH.

Application filed April 25, 1927. Serial No. 186,541.

The invention relates to railways, and more especially to the switch mechanisms thereof.

An object of the invention is to construct a railway switch wherein there is employed a single switch point, with means for actuating such single switch point to direct a vehicle either along the main line or into the side lines.

Another object is to produce an efficient strong and durable switch which may be economically constructed and operated.

Other objects and advantages will herein-after appear:

The views of the drawings are as follows:

15 Figure 1 is a plan of a section of railway track showing a switch installed therein constructed according to the preferred embodiment of my invention, the switch being set with the main line open;

20 Fig. 2 is a vertical section as seen from the line 2—2 of Fig. 1; and

Fig. 3 is a view similar to Fig. 2, showing the switch set to direct vehicles to or from the side line on to the main line.

25 Referring to the drawings, the railway track comprises the usual main line rails 5 and 6. The rails 5 are straight, while the rail 6 is curved, and with a rail 7 forms the inner end of a side line track. The rails may 30 be mounted on ties 8 in the usual manner with guard rails 9 and 10 disposed in the manner shown at the junction between the main and side line tracks.

In the present instance, the end of the rail 35 7 is provided with a movable switch point 11. This switch point has an L-shaped portion 12, to which is pivoted, as indicated at 13, one end of a horizontally disposed bar 14.

The bar 14 is arranged beneath the rails 40 and extends transversely of the track. Mounted on the bar 14 is a collar 15, while encircling the bar is another collar 16. If so desired, the collar 16 may be in the form of a vertical flange that is disposed on the inner 45 end of a plate 17.

The plate 17 has a slot 18 formed longitudinally therein, in which the bar 14 may be disposed, the slot serving as means for guiding the bar, as will be readily understood.

50 Between the collars 15 and 16, the bar 14 is encircled by an expansible spring 19.

The end of the bar 14 opposite to the pivot 13 has pivotally connected thereto, as indicated at 20, an operating arm 21.

55 The arm 21 is also disposed in the slot 18 of the plate 17, and near its outer end is

provided with a depending V-shaped lug 22.

The bottom of the slot 18 is terminated adjacent to the normal position of the lug 22 so as to provide a step 23. The step 23 is slightly undercut and the lug 22 is adapted to be latched thereagainst in the manner shown in Fig. 2. When the lug 22 is thus latched the switch point 11 will be set so as to permit a vehicle to pass along the main line 65 track in either direction.

In order to permit the end of the arm 21 to be easily raised or lowered, a loop 24 is formed in the end thereof adjacent to the lug 22.

70 The invention is, of course, susceptible to various modifications and adaptations.

In order to move the switch point or tongue 11 to a position to direct a vehicle onto the siding it is necessary to raise the arm 21 75 manually until the point of the undercut lug 22 thereon is free of the undercut step or shoulder 23 on the plate 17, whereupon the spring 19 will move the switch point 11 into contact with the rail 5 of the main line track, so the spring 19 thereafter resiliently maintaining the switch point 11 in this position.

In standard railway construction the switch points of all sidings connecting with main line tracks point in the direction of 85 traffic over the particular main line track with which the siding is connected, thus the flange of one of the foremost wheels of a train or vehicle moving in the direction indicated by the switch point 11 will pass between the 90 said switch point 11 and the rail 5, moving the switch point transversely until the lug 22 on the arm 21 again falls behind the undercut shoulder 23, which thereafter rigidly maintains the switch point 11 in this position 95 and again permits movement of vehicles in both directions along the main track.

Upon referring to Fig. 1, it will be noted that the second rail of the main line track is not provided with a spring tongue, as is 100 the usual practice, but is merely grooved to permit the passage of the flanges of vehicle wheels when the vehicles are passing from the main track to the siding or vice versa.

105 The invention claimed is:

1. In combination with a main track comprising a pair of spaced substantially straight rails and a side track comprising a pair of spaced curved rails extending substantially tangent to the rails of said main track, one of said side track curved rails being 110 formed continuous with the corresponding

straight rail of the main track, the portion of said rail of said main track adjacent the curve being beveled and spaced from said curve to permit the passage of the flanges 5 of vehicle wheels moving around said curve, the second rail of said main track being substantially straight and unbroken throughout and the second rail of said side track terminating in a spring switch tongue adapted to engage said unbroken rail of the main track; a plate extending transversely of and located under said tracks, a flange on said plate, a rod connected at one end to said spring tongue and extending through an opening in said 10 flange, a collar secured to said rod between said spring tongue and said flange, a spring coiled around said rod between said collar and said flange for moving and resiliently maintaining said spring tongue in contact 15 with said unbroken straight rail of the main track, an arm pivoted to the opposite end of said rod, an undercut lug on said arm adapted to engage a correspondingly undercut shoulder on said plate, for positively holding the 20 point of said opening switch tongue away from the said unbroken straight rail of the main track when the flange of a wheel of a vehicle moving along the main track in the direction in which said switch tongue is pointing, passes between said tongue and the adjacent unbroken straight rail of the main track for permitting subsequent passage of vehicles in both directions along said main track. 25

3. In combination with a main track comprising a pair of spaced substantially straight rails and a side track comprising a pair of spaced curved rails extending substantially tangent to the rails of said main track, one of said side track curved rails being formed continuous with the corresponding straight rail of the main track, the portion of said rail of said main track adjacent the curve being beveled and spaced from said curve to permit the passage of the flanges of vehicle wheels moving around said curve, the second rail of said main track being substantially straight and unbroken throughout and the second rail of said side track terminating in a spring switch tongue adapted to engage said unbroken rail of the main track; a plate extending transversely of and located under said tracks, a flange on said plate, a rod connected at one end to said spring tongue and extending through an opening in said flange, a collar secured to said rod between said spring tongue and said flange, a spring coiled around said rod between said collar and said flange for moving and resiliently maintaining said spring tongue in contact with said unbroken straight rail of the main track, an arm pivoted to the opposite end of said rod, an undercut lug on said arm adapted to engage a correspondingly undercut shoulder on said plate, for positively holding the point of said opening switch tongue away from the said unbroken straight rail of the main track when the flange of a wheel of a vehicle moving along the main track in the direction in which said switch tongue is pointing, passes between said tongue and the adjacent unbroken straight rail of the main track for permitting subsequent passage of vehicles in both directions along said main track. 30

2. In combination with a main track comprising a pair of spaced substantially straight rails and a side track comprising a pair of spaced curved rails extending substantially tangent to the rails of said main track, one of said side track curved rails being formed continuous with the corresponding straight rail of the main track, the portion of said rail of said main track adjacent the curve being beveled and spaced from said curve to permit the passage of the flanges of vehicle wheels moving around said curve, the second rail of said main track being substantially straight and unbroken throughout and the second rail of said side track terminating in a spring switch tongue adapted to engage said unbroken rail of the main track; a plate extending transversely of and located under said tracks, a flange on said plate, a rod connected at one end to said spring tongue and extending through an opening in said flange, a collar secured to said rod between said spring tongue and said flange, a spring coiled around said rod between said collar and said flange for moving and resiliently maintaining said spring tongue in contact with said unbroken straight rail of the main track, an arm pivoted to the opposite end of said rod, an undercut lug on said arm adapted to engage a correspondingly undercut shoulder on said plate, for positively holding the point of said opening switch tongue away from the said unbroken straight rail of the main track when the flange of a wheel of a vehicle moving along the main track in the direction in which said switch tongue is pointing, passes between said tongue and the adjacent unbroken straight rail of the main track for permitting subsequent passage of vehicles in both directions along said main track, and a hand grip on said arm whereby the arm may be moved relative to said plate, for disengaging said lug from said shoulder and thereby permitting said spring to reset said switch tongue, said plate having a groove in which said rod and said arm are located, said undercut shoulder being formed in the bottom of said groove. 35

for positively holding the point of said opening switch tongue away from the said unbroken straight rail of the main track when the flange of a wheel of a vehicle moving along the main track in the direction in which said switch tongue is pointing, passes between said tongue and the adjacent unbroken straight rail of the main track for permitting subsequent passage of vehicles in both directions along said main track, and a hand grip on said arm whereby the arm may be moved relative to said plate, for disengaging said lug from said shoulder and thereby permitting said spring to reset said switch tongue. 40

3. In combination with a main track comprising a pair of spaced substantially straight rails and a side track comprising a pair of spaced curved rails extending substantially tangent to the rails of said main track, one of said side track curved rails being formed continuous with the corresponding straight rail of the main track, the portion of said rail of said main track adjacent the curve being beveled and spaced from said curve to permit the passage of the flanges of vehicle wheels moving around said curve, the second rail of said main track being substantially straight and unbroken throughout and the second rail of said side track terminating in a spring switch tongue adapted to engage said unbroken rail of the main track; a plate extending transversely of and located under said tracks, a flange on said plate, a rod connected at one end to said spring tongue and extending through an opening in said flange, a collar secured to said rod between said spring tongue and said flange, a spring coiled around said rod between said collar and said flange for moving and resiliently maintaining said spring tongue in contact with said unbroken straight rail of the main track, an arm pivoted to the opposite end of said rod, an undercut lug on said arm adapted to engage a correspondingly undercut shoulder on said plate, for positively holding the point of said opening switch tongue away from the said unbroken straight rail of the main track when the flange of a wheel of a vehicle moving along the main track in the direction in which said switch tongue is pointing, passes between said tongue and the adjacent unbroken straight rail of the main track for permitting subsequent passage of vehicles in both directions along said main track, and a hand grip on said arm whereby the arm may be moved relative to said plate, for disengaging said lug from said shoulder and thereby permitting said spring to reset said switch tongue, said plate having a groove in which said rod and said arm are located, said undercut shoulder being formed in the bottom of said groove. 45
